WILLIAM KREIELSHEIMER, OF NEW YORK, N. Y.

DESIGN FOR A SCARF OR SIMILAR ARTICLE

Application filed February 24, 1931. Serial No. 38,799. Term of patent 3½ years.

To all whom it may concern:

Be it known that I, WILLIAM KREIELSHEIMER, a citizen of the United States, residing in Queens County, city of New York, State of New York, whose post-office address is 60 Leonard Street, city of New York, county of New York, and State of New York, have invented a new, original, and ornamental Design for a Scarf or Similar Article of which the following is a specification reference being had to the accompanying drawing, forming part thereof:

The figure of the drawing is a plan view of

approximately a quarter section of a scarf, or similar article, showing my new design.

The dot and dash lines shown in the drawing define a one-quarter section of the motif constituting the complete design. The other three sections of the design are identical and continue in proper relation to the section shown.

I claim:

The ornamental design for a scarf or similar article substantially as shown and described.

WILLIAM KREIELSHEIMER.
